UNITED STATES PATENT OFFICE.

HENRY S. BELDEN, OF CANTON, OHIO.

STREET-LAMP.

SPECIFICATION forming part of Letters Patent No. 286,763, dated October 16, 1883.

Application filed April 15, 1882. (No model.)

To all whom it may concern:

Be it known that I, HENRY S. BELDEN, a citizen of the United States, residing at Canton, in the county of Stark and State of Ohio, have invented certain new and useful Improvements in Street-Lamps, of which the following is a specification, reference being had therein to the accompanying drawings.

Figure 1 is a view of my improved apparatus, shown attached to an ordinary street-lamp. Fig. 2 is a vertical section of the stop-cock.

A represents the body of an ordinary street-lamp, provided with a vertical or somewhat sloping wall or walls, A'.

B is a reservoir attached in any of the usual ways to the lamp.

C represents the burner, connected with the reservoir by means of the feed-pipe D. This pipe D is connected to the atomizer I by means of elbow-joint E, which is provided with screw-threaded sockets e e' for their reception.

e' is a small supplemental tube attached to the rear side of the elbow-joint E. It is internally screw-threaded, and extends through the wall A' of the lamp, to provide a bearing for the valve-screw F. The head or handle F' of said valve-screw is outside of the lantern, and permits a ready manipulation of the valve within the lantern.

g' is a conical valve-seat formed around the aperture g, adapted to receive and fit tightly the pointed or conical end of the valve-screw F, which forms the valve. Those constructions in which the oil-conducting devices and the regulating-valve or stop-cock are situated upon the outside of the lantern have been found very objectionable from the interference caused by ice and snow in winter, and have been faulty, moreover, from the fact that the supply-pipe cannot be supported securely. Upon the other hand, those constructions in which both the valve and the valve-screw were located entirely on the inside of the lantern have been found objectionable from the fact that on manipulating them the lamp-door must be frequently opened and closed several times before the burner is in proper working

order, and from the fact that the handle of the screw becomes very hot from the heat of the burner.

One object of this invention is to make a conduit for a street-lamp burner in such shape that it shall have no corners, angles, recesses, or pockets which can serve as receptacles to catch and stop impurities that may be in the oil, but shall allow all impurities, especially water, to pass directly from the reservoir through to the burner. Heretofore conduits for street-lamps have been made with receptacles (generally called "traps") to arrest and catch the water that may have found access to the reservoir or other part of the attachment; but these street-lamps are subject to more or less rocking or motion caused by the wind or otherwise, and the water pockets or traps, when the lamps are thus moved, often throw back into the oil-conduit the water which they have collected, and this water passes on to the burner and immediately extinguishes the light. This same result is caused often by a rapid flow of oil from a new reservoir, or a newly-filled one, the oil running into the water pocket or trap, and carrying out of it some of the water previously collected therein.

Another object of the invention is to provide a street-lamp with a conduit made of tubing which shall have no bends or curves in the piece or pieces of tubing, but which shall have, however, two or more parts inclined to each other, one part extending downwardly from the reservoir and the other attached to the burner, the two parts of the tubing being detachably connected as near as possible at the lower end of the down pipe. The pieces of tubing of which these conduits are made must be frequently cleaned, and when they are bent or curved, as they have been heretofore, the cleaning is much more difficult than when they are made perfectly straight.

It will be seen that with my construction any liquid passing from the reservoir will flow continuously through the conduit and directly to the burner. Therefore in case water gets into any part of the attachments it will

pass immediately down to the burner, and not be intercepted during its flow through the pipes.

Many advantages are incident to a construction of this nature. When the lamp-lighter undertakes to light a lamp having a conduit of this character, he perceives at once whether there is any water in the burner, the oil, or the attachment, because the water, being unimpeded, will immediately come to the burner and prevent his lighting it; but in those constructions having receptacles or traps for the water there will not necessarily be a prevention of ignition, as the water will be temporarily stopped, and therefore the lighter may be deceived, and after leaving the lamp the water will be thrown into the conduit again in some of the ways and with the results above set forth. Should a lighter using a lamp of my construction find that there is water in the burner he can immediately detach the atomizer, tubing, and the burner and replace them with others which are dry. Before doing this he cuts off the supply of oil by the valve F. Therefore it is very important, in order to obtain the best results with lamps of this character, that the conduits should be formed without any bends or crevices or receptacles, so that there shall be provided for the liquid a substantially unbroken passage to prevent the stopping of water or other impurities, and also that the regulating devices should be arranged to project through the wall of the lamp, so as to be readily controlled for cutting off the supply both when there is danger of accident and when it is necessary to detach a wet burner.

I am aware that street-lamps have been heretofore constructed with four or more pieces of tubing or pipes on the inside of the lantern, two or more of the pipes lying in different planes for conducting downward, and two or more also lying in different planes for conducting horizontally or inward; and I do not claim, broadly, such devices as my invention. Such construction is shown, for instance, in an English patent to Hearson, No. 1,769, of 1877; but the devices constructed after this manner are not capable of the convenient manipulation of which mine is; nor are they constructed as simply, or so as to accomplish the same purposes. In those referred to the horizontal pipe connected directly to the burner has not been utilized as a retort or atomizer, the retort portion of the conduit being considerably above the burner, and therefore there is necessity of several intervening parts, which I avoid. Moreover, these devices do not allow of a cutting off of the supply of oil in case of a large flame inside, unless the hand of the operator be thrust inward through the lantern to the cut-off valve situated at a suitable distance above the burner. When the parts are constructed and arranged as I have shown and described, the flow of oil can be immediately stopped from the outside, and

the retort, and the burner connected directly to the retort, can be detached if it is necessary to supply a dry retort. To remove the retort from the devices used heretofore has necessitated the taking out of a large part of the attachment, which is a matter of great inconvenience and difficulty, whereas in my case it can be done by simply turning the burner round two or three times to disengage the connection of the retort with the down pipe.

What I claim is—

1. In a street-lantern attachment, the combination of the unbent down pipe D, the burner C, provided with a threaded socket, e, the unbent packed removable retort-pipe I, screw-threaded at both ends and lying from end to end substantially at right angles to the burner, the elbow E, having the screw-threaded socket e, engaging with the down pipe D, the screw-threaded socket e², projecting through the wall of the lantern in the horizontal plane of the burner, the screw-threaded socket e', engaging with the end of the unbent pipe I, whereby the burner can be held in the proper position, and in connection with the packed retort-pipe I, can be disconnected from the lantern by rotating it on an axis substantially at right angles to the burner, and the valve-screw F F', passing through the wall of the lantern, whereby the flow of oil can be shut off and the flame stopped without the necessity of inserting the hand into the lantern, said elbow E and the unbent pipes being constructed and arranged, substantially as set forth, to not have pockets or traps for the gathering of water.

2. In a street-lantern attachment, the combination of the unbent down pipe D, the burner C, the unbent packed retort-pipe I, situated at right angles substantially to the burner, the elbow E, having the socket e to engage with the down pipe D, the socket e' at an obtuse angle to the socket e, to allow the retort-pipe I and burner C to be held in proper position, and the threaded socket e², situated in the horizontal plane of the burner, and projecting outwardly through the wall of the lantern, and the valve-screw F F', having its head outside of the lantern, all of said parts being arranged substantially as set forth, to prevent the collection of water, and to permit the cutting off of the oil and stopping of the flame from the outside, in order that the retort-pipe I, in connection with the burner, may be unscrewed by rotating them on the axis of the valve-screw F F', substantially as set forth.

3. In a street-lantern attachment, the combination of the unbent down pipe D, the burner C, the unbent packed detachable retort-pipe I, the elbow having the socket e', which engages with the unbent retort-pipe I, and having the socket e², which projects through the wall of the lantern, and has the internally-threaded part, e³, and the bottom

wall, *e*, situated on or nearly on the horizontal plane of the bottom of the valve-duct *g*, to avoid the collection of water, and the valve-screw *F* *F'*, passing from the outside to the inside of the lantern-wall, and movable directly toward and from the end of the removable pipe *I*, substantially as and for the purposes set forth.

In testimony whereof I affix my signature in presence of two witnesses.

HENRY S. BELDEN.
